UNITED STATES PATENT OFFICE

170,294

HOBBYHORSE

Russell Wenkstern, Mound, Minn., assignor to Moulded Products, Inc., Spring Park, Minn., a corporation of Minnesota

Application July 8, 1950, Serial No. 11,027

Term of patent 14 years

(Cl. D34—15)

To all whom it may concern:

Be it known, that I, Russell Wenkstern, a citizen of the United States of America, residing at Mound, county of Hennepin, State of Minnesota, whose post office address is Mound, Minnesota, have invented a new, original, and ornamental Design for Hobbyhorse, of which the following is a specification, reference being had to the accompanying drawing forming a part thereof, in which:

Fig. 1 is a perspective view of a hobbyhorse showing my new design and looking toward the front and left side of the structure; and

Fig. 2 is a perspective view of my hobbyhorse taken from the rear and right side of the structure.

I claim:

The ornamental design for a hobbyhorse, substantially as shown.

RUSSELL WENKSTERN.
